UNITED STATES PATENT OFFICE.

THOMAS HENRY TREGELLAS, OF IUKA, KANSAS.

PUMP-ROD LIFTER.

SPECIFICATION forming part of Letters Patent No. 741,566, dated October 13, 1903.

Application filed April 15, 1903. Serial No. 152,711. (No model.)

To all whom it may concern:

Be it known that I, THOMAS HENRY TREGELLAS, a citizen of the United States, and a resident of Iuka, in the county of Pratt and State of Kansas, have made certain new and useful Improvements in Pump-Rod Lifters, of which the following is a specification.

My invention is an improvement in devices for lifting or pulling pump-rods; and the invention consists in certain novel constructions and combinations of parts whereby the rods may be readily lifted, devices being supplied for securing such lifting action by an operation similar to that of pumping, all of which will be hereinafter described.

In the drawings, Figure 1 is a front elevation, Fig. 2 a side elevation, and Fig. 3 a perspective view, of my improved devices as in use. Figs. 4 and 5 illustrate the devices used in clamping the framing to a well tube or casing, and Fig. 6 illustrates a construction of lifter for pulling the rods directly by hand.

In the accompanying drawings, A represents a portion of a pump tube or casing projecting above the ground B and forming a support for the detent or holding-frame A, as well as for the connection of the main frame, which is shown as consisting of the posts D. The posts D, of which I use two, as best shown in Fig. 3, extend upwardly alongside the tube A and are secured thereto by the stirrup-clips E passing around the tube A and thence through the plate E', receiving the nuts E', blocks F being arranged to bear against the opposite side of the tube A from the stirrup E and having the shanks F', which fit between the posts D and hold the same apart, as best shown in Fig. 3 of the drawings. The posts D above the upper stirrup E are preferably deflected rearwardly, as shown at D', and support at their upper ends the operating-lever G, which is pivoted at G' between the posts D, providing the handle-arm G² and the shorter arm G³ for connection with the lifting-frame H.

The frames C and H are alike, consisting of the side plates C' H', the fixed dogs C² H², and the pivoted dogs C³ and H³, said dogs being supported and arranged to operate between the side plates of their respective frames and the dogs C³ and H³ being arranged to yield against upward movement, but to

bind against any downward movement of the pump-rods I. It will be understood that the dogs C² and H² are held from movement independently of the side plates and form back-bearings for the pump-rods in the lifting and holding operations of the frames H and C, and the dogs C³ and H³ operate pivotally between their respective side plates C' and H' and the plates may be provided with a plurality of openings—such as shown, for instance, at C' in Fig. 1—so the dogs C³ and H³ can be adjusted toward and from their fixed dogs C² and H² in order to adapt the devices to operate upon rods of different diameters. Hangers J connect with the opposite ends of the frame H and are connected by the yoke K with the arm G³ of the lever G, so said lever may operate to reciprocate the lifting-frame H as desired.

In operation when it is desired to lift the rods the post-frame may be secured to the tube or casing A by the devices before described and the holding-frame C be slipped down upon the rod I to a position in which it will rest upon the upper end of the tube or casing A, as shown in Figs. 1, 2, and 3. The lifting-frame may now be slipped down upon the rod I until it occupies a position above the frame C and the handle-lever be connected with the lifting-frame by the devices before described. As the lifting-frame is raised its dog H³ will bind the rod between it and its fixed dog H² and will lift the rod, the latter slipping up between the fixed and movable dog of the holding-frame C to the full extent of the upward stroke of the lifting-frame. When the lifting-frame is lowered on its return stroke, the dogs of the holding-frame will bind the pump-rod and prevent the same from dropping until the lifting-frame has been adjusted to its lowermost position, ready to begin its return stroke. The lifting-frame may thus be operated reciprocally to raise the rods, the holding-frame being supported on the upper end of the tube or casing and operating as a detent by which to support the rods while the lifting-frame is being lowered for a fresh hold.

In Fig. 6 I show one of the dog-frames provided with handles L, so the rod M may be raised directly by hand.

Manifestly the device may operate upon

round rods, as shown at M in Fig. 6, or angular rods, as shown at I in Fig. 3, and may also be used for pulling rods of wood or iron, and the operation may be practically continuous like that of pumping except for the time necessary to uncouple the sections of the rods as they are lifted out of the well.

Having thus described my invention, what I claim as new, and desire to secure by Letters Patent, is—

1. The combination substantially as herein described of the pump tube or casing, the post-frame having the pair of posts fitting alongside and projecting above the tube, the stirrups fitting around the tube, the plates and nuts for securing the ends of the stirrups at the outer side of the post-frame, the blocks F having lugs fitting between the posts of the frame and body portions abutting the tube or casing, the holding-frame supported on the upper end of the tube and provided with dogs to operate as detents upon the rod, the lifting-frame above the holding-frame and having dogs to operate upon the rod, hangers connected with the opposite ends of the lifting-frame, the yoke connected with said hangers and the lever pivoted between the posts and connected with the yoke substantially as set forth.

2. An apparatus for lifting pump-rods comprising the frame having upright posts, clamps for securing said frame to the pump tube or casing, a lever pivoted to the said frame, a yoke connected between its ends with said lever, a lifting-frame having dogs to engage with the pump-rod, hangers connecting the

ends of said lifting-frame with the yoke, and a detent device to coöperate with the lifting-frame in pulling the rods substantially as set forth.

3. The combination with a pump-tube and the detent-frame supported thereon of a main frame, devices for securing the main frame to the well-tube, a lifting-frame provided with means for engaging the pump-rod, a handle-lever pivoted to the main frame and devices connecting the handle-lever with the lifting-frame substantially as set forth.

4. The combination of the pump tube or casing, the main frame having posts extending alongside and clamped to the tube or casing and being deflected above the tube or casing, the holding devices supported on the tube or casing, and the lifting devices above the holding devices and including a lever pivoted to the deflected portion of the main frame substantially as set forth.

5. The combination of the pump tube or casing, the main frame comprising the posts spaced apart, the stirrups fitting around the pump tube or casing, the plates and nuts securing the stirrups in connection with the posts, the opposing blocks having lugs fitting between the posts and body portions fitting against the tube or casing, and the lifting and holding devices for operating upon the rods substantially as set forth.
